SYSTEM OF CONTROL.

1,399,468.

Specification of Letters Patent.

Patented Dec. 6, 1921.

Application filed October 18, 1917. Serial No. 196,395.

To all whom it may concern:

Be it known that I, KARL A. SIMMON, a citizen of the United States, and a resident of Edgewood Park, in the county of Allegheny and State of Pennsylvania, have invented a new and useful Improvement in Systems of Control, of which the following is a specification.

My invention relates to systems of control and particularly to the control of so-called "one-man" or "quick-service" cars for operation thereof from a distance when running over railroad crossings and the like.

The object of my invention is to provide a system of the above-indicated character whereby readily portable means for effecting operation of the vehicle motor or motors from a point external to the vehicle is provided, and interlocking means, preferably embodying a change of location of the familiar master-reverser operating handle, is employed for preventing concurrent operation from the vehicle itself.

More specifically stated, it is the object of my invention to provide, in conjunction with a motor-operating system of any well-known type, a relatively simple control apparatus of the cable-retrieving type, whereby the car operator, after approaching a railroad crossing or the like, may readily govern the vehicle operation from a point on the far side of the railroad crossing and the operating cable will be automatically retrieved or paid out as the vehicle moves in the one or the other direction.

My invention may best be understood by reference to the accompanying drawings, wherein Figure 1 is a diagrammatic view of the main circuits of a system of control to which my invention may be applied; Fig. 2 is a diagrammatic view of a set of auxiliary governing circuits embodying the invention; Fig. 3 is a view, partially in elevation and partially in section, of an auxiliary control apparatus embodying the principles of my present invention, and Fig. 4 is a general view showing my invention in use at a railroad crossing.

Referring first to Fig. 4, the view illustrates a safety or quick-service car 101 that is supplied with energy from a trolley and grounded rails 102 in accordance with a familiar practice. The vehicle is shown as

located on one side of a steam railroad crossing or the like including tracks 103 and 104, while the single car operator 105 is situated on the remote side of the railroad crossing. The operator holds in one hand a push-button device 18 that is electrically connected, through a flexible cable 33, to the control apparatus on the vehicle 101, as subsequently more fully described, to effect remote control of the vehicle and cause it to safely cross the railroad crossing.

Referring to Fig. 1 of the drawings, the system shown comprises supply-circuit conductors Trolley and Ground; a plurality of main driving motors respectively having commutator-type armatures A1 and A2 and field windings F1 and F2 of the series type; a reversing switch RS, preferably of a familiar electrically-controlled type, as indicated in Fig. 2, but here conventionally shown for the sake of simplicity and clearness; a line switch LS; a current-limit switch L; an accelerating resistor 1; and a drum controller 2 having an actuating mechanism 3 for governing the acceleration of the driving motors by suitably varying the resistor 1 and changing over the motor connections from series to parallel relation, in accordance with the familiar "shunting" type of transition. However, since the particular main-circuit connections are immaterial to my present invention, which is capable of application to any well-known motor-operating system, no further description thereof is deemed necessary, with the exception of describing the actuating mechanism 3, which is preferably, but not necessarily, employed in connection with my invention.

The actuating mechanism 3 is of a familiar electrically-controlled, pneumatically-operated type, comprising a pinion 5, which is secured to the operating shaft 6 for the drum controller 2 and is adapted to mesh with a horizontally-movable rack member 7, the opposite ends of which constitute pistons 8 and 9 that travel within appropriate operating cylinders 10 and 11, respectively. A normally open valve 12, having an actuating coil "Off", communicates with the outer end of the cylinder 10, while a normally closed valve 13, having an actuating coil "On", is associated with the outer end of

the other cylinder 11. Fluid pressure from any suitable source (not shown) may be conveyed to the valves 12 and 13, whereby the apparatus is normally biased to the illustrated extreme position.

The mechanical operation of the actuating mechanism 3 may be set forth as follows:

Upon concurrent energization of the actuating coils On and Off, the initial unbalanced fluid-pressure conditions in the apparatus are reversed; that is, fluid pressure is admitted to the cylinder 11 through the valve 13 and is exhausted from the other cylinder 10 through the valve 12 to the atmosphere. Consequently, a movement of the pistons 8 and 9 and of the controller 2, toward the left in the illustrated case, ensues. To arrest such movement at any time, it is merely necessary to deenergize the off coil, whereupon balanced high-pressure conditions obtain in the mechanism and a positive and reliable stoppage thereof is effected.

To produce a return movement of the device, the actuating coils On and Off are concurrently deenergized, whereupon fluid-pressure conditions revert to the original state and the desired backward movement is effected.

Referring now to Fig. 2, the auxiliary system shown employs the supply-circuit conductors Trolley and Ground, a suitably reduced control voltage being obtained through the agency of a control resistor 15, in accordance with a familiar practice. The system further comprises the actuating coils for the line switch LS, for the actuating mechanism 3 and for the reversing switch RS, together with suitable electrical interlocks of a familiar type; an auxiliary resistor 16, a brake-controlling coil marked "Brake;" and a battery B for energizing such coil under predetermined conditions to be set forth to release the brake application; a master controller MC and a master reverser MR for primarily governing the operation of the system; and a portable switching device 18 of the well-known multiple push-button type.

One form of apparatus embodying the principles of my invention is shown in Fig. 3 in conjunction with the switching device 18, which comprises a suitable shell or incasing member 20 and a plurality of push buttons 21, 22 and 23 which are normally held in their outer or open-circuit position by suitable springs, as illustrated in Fig. 2. A retrieving mechanism 24, represented by the coiled cable in Fig. 2, and shown in section in Fig. 3, comprises a rotatable drum or hollow spool having end-plates 32, a multi-conductor cable 33 being wound upon the cylindrical body portion of the spool. A plurality of externally grooved hubs 34 and 35 are secured to the outer faces of the respective end-plates 32 for performing the double

function of aiding to support the retriever drum upon a centrally-located stationary shaft 36 and to carry an electrical interlocking plate 30, as hereinafter more fully set forth.

One end 37 of the stationary shaft 36 is threaded to permit axial movement of the retriever drum toward the left as the flexible cable 33 is paid out, and a torsion spring 38 is located within the drum, having its respective ends secured to the shaft 36 and to the left-hand end-plate 32, for the purpose of automatically retrieving the cable 33 or maintaining it taut under all operating conditions.

For the purpose of maintaining the desired electrical connections of the several conductors forming the cable 33 during rotative movement of the retriever drum, a plurality of collector rings or bands 39 surround the drum, being connected to the respective cable conductors in any suitable manner.

The interlocking plate 30 comprises a slab or base 40 of insulating material upon which are mounted a plurality of contact strips or blocks 41, 42 and 43 that respectively engage pairs of stationary control fingers 45, 46 and 47 in predetermined positions of the retrieving device, such control fingers being preferably mounted upon a finger-base 44 of a familiar type, for effecting the desired external-circuit connections that are shown in Fig. 2. A further set 48 of control fingers is mounted upon the slab 40 or an extension thereof for engaging the band or ring contact members 39 of the drum. A suitable cable 49 is provided for connecting the control fingers 48 to a plurality of terminals or binding posts 50 that are located upon the finger-base 44, whereby the external circuit connections that are shown in Fig. 2 may be readily made.

The interlocking plate 30 is adapted to move longitudinally in accordance with the concurrent rotative and axial movement of the retriever drum, such action being effected by reason of mounting the interlocking plate upon a plurality of arms 51 and 52 that terminate in bands or rings loosely fitting within the grooves around the drum hubs 34 and 35, respectively.

A latching device 31 for the retrieving apparatus comprises an intermediately pivoted bar or rod 55, one end of which is provided with a latch or lock 56 to suitably engage the right-hand end-plate 32, whereby movement of the retriever drum in either a rotative or an axial direction is prevented. The other end of the rod 55 has mounted upon it a half drum 57, or the equivalent, which carries a plurality of contact segments 58 and 59 for engaging suitable control fingers 60 in accordance with the position of the latching device, as hereinafter described in detail in connec-

tion with Fig. 2. The latching device 31 is adapted to occupy a position marked "Unlatched" as well as the illustrated position designated as "Latched." The familiar 5 operating handle or lever 61 of the master reverser MR is preferably employed for manually actuating the interlocking device from the one to the other of its positions, whereby it is necessary for the vehicle operator, after stopping the car near a railroad crossing, to actuate his master reverser to the "off" position, remove the operating handle 61 and apply it to the interlocking device 31, before the retrieving 10 mechanism can become operative for the intended purpose. In this way, the normal operation of the driving motors from the vehicle platform is prevented during the time that the operator is controlling the 15 vehicle from a distant point by means of the external control apparatus.

It will be understood that the entire apparatus of Fig. 3 may be appropriately mounted in any convenient location within 20 the car vestibule, which need not be set forth here.

To effect normal acceleration of the driving motors, the master reverser MR is moved to its "forward" position, for example, and the master controller is actuated to its operative position *a*. A circuit is thereby established from the positive terminal of the battery B through the "brake" coil, conductor 106, contact segment 98 or 25 99 of the master reverser in the one or the other of its operative positions, and conductor 101 to ground, whence circuit is completed to the negative battery terminal. In this way, the illustrated vehicle braking 30 system is rendered inoperative during normal car operation, with the master reverser occupying an operative position.

Another auxiliary circuit is established from the trolley through conductor 65, contact fingers 66 and 67, which are bridged by 35 contact segment 68 of the master controller, and thence through control resistor 15 to ground.

A further circuit is established from an 40 intermediate tap-point 69 of the control resistor through contact strip 41 of the interlocking plate 30 (Fig. 3), contact segment 58 of the latching device 31, when occupying its illustrated "latched" position, conductors 70 and 71, the actuating coil of the switch LS, contact segment 72 of the main controller 2 in its initial position, contact segment 73 of the main reversing switch RS in its "forward" position, conductors 45 74 and 75, contact segment 76 of the master reverser in its "forward" position, conductor 77, contact fingers 78 and 79, which are bridged by contact segment 80 of the master controller, and conductor 81 to ground.

50 As soon as the line switch LS has closed

to connect the driving motors to the supply circuit, a holding circuit for the actuating coil of the switch is formed by the bridging of the contact segment 72 by an interlock LS-in. 70

Since the relation of the forward and reverse coils for the main reverser RS to the remainder of the system is familiar to those skilled in the art, and furthermore, has no bearing upon the present invention, it is 75 deemed unnecessary to describe such circuits in detail.

A further auxiliary circuit is established, upon the closure of the line switch LS, from a second intermediate point 82 of the control resistor 15 through the actuating coil On and an interlock LS-in to another intermediate tap-point 83 of lower voltage. However, no movement of the main controller 2 occurs until the off coil is energized, which takes place, whenever the limit switch L occupies its lower position, by the completion of another circuit from the tap-point 82 through the actuating coil Off, contact disk 85 of the limit switch L and 85 interlock LS-in to the tap-point 83. In this way, the main controller 2 is actuated through its various positions, in accordance with the movements of the limit switch L, to suitably manipulate the variable resistor 90 1 and change over the driving motor connections from series to parallel relation, as will be understood.

To effect the external control of the vehicle when a railroad crossing or the like 100 is approached, the vehicle is stopped on the near side of the crossing, and the master reverser MR is manipulated by the usual operating handle 61 to the "off" position, which does not operate the main reversing 105 switch RS, but, upon removal of the operating handle 61, control of the motor operating system by the master controller is prevented by reason of the familiar mechanical interlocking device (not shown) that is provided in all modern types of control apparatus. 110

Furthermore, the vehicle brakes are automatically applied, as soon as the master reverser occupies its "off" position, by reason 115 of the interruption of the previously-traced circuit through the "brake" coil.

The master-reverser operating handle 61 is then applied to the latching device 31 (Fig. 3) which is thereby actuated to its 120 "unlatched" position. The motorman may then take the push-button switching device 18 and cross the railroad tracks, the flexible cable 33 in the meanwhile being paid out as necessary by reason of the helical movement 125 of the retriever drum along the threaded shaft 36, in opposition to the action of the coil spring 38. Such movement of the retrieving device interrupts the auxiliary circuit including contact block 41, and closes 130

new auxiliary circuits including contact blocks 42 and 43, of the interlocking plate 30.

Consequently, by pressing the push-button 21 of the switching device 18, the following 5 circuit through the actuating coil "Brake" is energized and the braking system is rendered inoperative: from the lower terminal of the "brake" coil through contact block 43 of the interlocking plate 30 in an operative 10 position, conductors 97 and 97^a, push-button 21, and thence through conductors 98, 95 and 95^a to ground.

Upon closing the push-button 22, in addition to the button 21, a new circuit is established 15 from the trolley through conductors 65 and 90, control fingers 91 and 92, which are bridged by contact segment 93 of the master reverser in its "off" position, voltage-reducing resistor 16, contact block 42 of the 20 retrieving device in any operative position, contact segment 59 of the latching device 31 in its "unlatched" position, and thence through conductor 70 and the actuating coil of the line switch LS to conductor 74, as 25 previously described, circuit being completed therefrom through conductor 94, cable 33 of the retrieving device 24, conductor 94^a, push-button 22 and conductors 95 and 95^a to ground.

30 The line switch LS is thus closed to reconnect the driving motors to the supply circuit, but the actuating coils On and Off for the main controller 2 are not energized in the previously-described manner, by reason of the master controller MC occupying its "off" 35 position. It will be understood, however, that if desired, the actuating coils On and Off may readily be reconnected by further contacts on the latching device 31 to be operative 40 during the period of external vehicle control also. The vehicle speed may of course be readily regulated by alternately pressing and releasing the accelerating button 22, whereby the car is alternately driven 45 and permitted to coast.

It will thus be seen that the control means normally employed, that is, when the motorman occupies his usual position on the front platform is adapted to effect operation of 50 the motor to a predetermined stage, that is, to full parallel relation, corresponding to maximum speed. On the other hand, when the portable control device 18 is employed by the motorman, the motor operation is carried 55 to a different stage, namely, to the slow-speed condition corresponding to the initial connection of the motors to the supply circuit with the resistor 1 also active.

Without a detailed tracing of circuits, it 60 will be understood that the remaining push-button 23 is employed for effecting reversed operation of the driving motors when the main reversing switch RS occupies its "reverse" position.

In this way, forward or reversed movement of the vehicle is controlled from the portable switching device 18, which, moreover, is adapted to act in the capacity of a "dead-man's release" feature, since, if the push-button 21 is relieved of pressure, by 65 reason of incapacitation of the motorman or by the switching device slipping from his hand, or, if the cable 33 is seriously damaged in any way to deenergize the circuit of the 70 brake coil, then the emergency brake is immediately applied to prevent the vehicle 75 from running away.

When the vehicle has passed the railroad crossing and has approached to within a short distance of the operator, the push-button 80 device 18 may be allowed to completely reassume its biased open-circuit position to effect the application of the vehicle brakes. Preferably, however, such action is automatically effected as soon as the retrieving 85 device returns to its illustrated initial position with the push-button device still operative, the previously-traced circuit including the contact block 42 of the interlocking plate 31 being thereupon interrupted to cause the 90 opening of the line switch LS.

When the portable switching device 18 has been returned to its normal position, the master reverser operating handle 61 may be utilized to return the latching device 31 to 95 its illustrated "latched" position to prevent further actuation of the retrieving device, and the operating handle 61 may then be reinserted in the master reverser to actuate it to the one or the other of its operative positions. Actuation of the master controller MC to govern the system in the previously-described normal manner is thus again permitted, and the braking system is again rendered inoperative by reason of the previously-described energizing circuit through the "brake" coil whenever the master reverser occupies an operative position.

It will be understood by those skilled in the art that in the case of a plurality of 110 motor-driven vehicles operating on the familiar multiple-unit principle, my invention may be readily applied to the external control of such a train through the agency of the usual train-line conductors.

I do not wish to be restricted to the specific circuit connections, structural details or arrangement of parts herein set forth, as various modifications thereof may be effected without departing from the spirit and 120 scope of my invention. I desire, therefore, that only such limitations shall be imposed as are indicated in the appended claims.

I claim as my invention:

1. In a system of vehicle control, the combination with an electric motor and means located upon the vehicle for normally governing the motor operation, of means for 125

- effecting motor operation from a point external to the vehicle and for preventing concurrent operation from the vehicle itself.
2. In a system of vehicle control, the combination with an electric motor and an operating system therefor, of means located upon the vehicle for normally governing said system, and means including flexible conductors for governing the system from selected points external to the vehicle and for retrieving or paying out said flexible conductors as the vehicle moves in the one or the other direction.
3. In a system of vehicle control, the combination with an electric motor and an operating system therefor, of means, including a removable operating handle, located upon the vehicle for normally governing said system, and means, including said handle in a different location, for governing the system from a point external to the vehicle.
4. In a system of vehicle control, the combination with an electric motor and an operating system therefor, of means, including a reversing switch having a removable operating handle, located upon the vehicle for normally governing said system, and means, including said handle in a different location after the reversing switch occupies a predetermined position, for governing the system from a point external to the vehicle.
5. In a system of vehicle control, the combination with an electric motor and an operating system therefor, of means, including a master reversing switch having a removable operating handle, located upon the vehicle for normally governing said system, and means, including said handle in a different location after the master reversing switch occupies its "off" position, for governing the system from a point external to the vehicle.
6. In a system of vehicle control, the combination with an electric motor and an operating system therefor, of means, including a reversing switch having a removable operating handle, located upon the vehicle for normally governing said system, and means, including said handle in a different location and including flexible conductors, for governing the system from selected points external to the vehicle and for retrieving or paying out said flexible conductors as the vehicle moves in the one or the other direction.
7. In a system of vehicle control, the combination with an electric motor and an operating system therefor, of means located upon the vehicle for normally governing said system, a braking system, and means, including a portable switching device, for governing said operating system from a point external to the vehicle and for automatically rendering said braking system op-
- erative whenever certain circuits of said switching device are deenergized.
8. In a system of vehicle control, the combination with an electric motor and an operating system therefor, of means located upon the vehicle for normally governing said system, a braking system, and means for governing said operating system from a point external to the vehicle and for automatically rendering said braking system operative when said external governing means is returned to its normal location upon the vehicle.
9. In a system of vehicle control, the combination with an electric motor and an operating system therefor, of means located upon the vehicle for normally governing said system, a braking system, and means, including a portable switching device, normally biased to open-circuit condition, for governing said operating system from a point external to the vehicle and for automatically rendering said braking system operative whenever said switching device occupies its biased position and whenever the device is returned to its normal location upon the vehicle.
10. In a system of vehicle control, the combination with an electric motor and an operating system therefor, of means, including a reversing switch having a removable operating handle, located upon the vehicle for normally governing said system, a braking system, and means including said handle in a different location and including flexible conductors for governing the system from selected points external to the vehicle and for retrieving or paying out said flexible conductors as the vehicle moves in the one or the other direction, said external governing means also including a portable switching device for automatically rendering said braking system operative when said flexible conductors are completely retrieved.
11. In a system of vehicle control, the combination with an electric motor and an operating system therefor, of means, including a master reversing switch having a removable operating handle, located upon the vehicle for normally governing said system, a braking system, and means, including said handle in a different location after the master reversing switch occupies its "off" position, for governing the system from a point external to the vehicle, said external governing means also including a portable switching device for automatically rendering said braking system operative whenever certain circuits of said switching device are deenergized while said reversing switch occupies its "off" position.
12. In a vehicle, control apparatus comprising a normally locked rotatable member, means for unlocking said member under

predetermined conditions, a multi-conductor cable wound on said rotatable member, a portable switching device connected to one end of said cable, and a circuit-making-and-breaking member actuated in accordance with the movements of said rotatable member.

13. In a vehicle, control apparatus comprising a normally, locked, helically movable drum, means for unlocking said drum under predetermined conditions of other apparatus upon the vehicle, a multi-conductor cable wound on said drum, a portable switching device connected to one end of said cable, and a circuit-closing and opening plate member actuated in accordance with the axial movements of said drum.

14. In an electric vehicle embodying a reversing switch and operating handle therefor, control apparatus comprising a helically movable drum, a circuit-changing device also adapted to normally lock said drum in a certain position, means for unlocking said drum by said operating handle when the reversing switch occupies its "off" position, a multi-conductor cable wound on said drum, a portable switching device connected to the free end of said cable, and a circuit-closing and opening plate member actuated in accordance with the axial movements of said drum.

15. In a system of vehicle control, the combination with a supply circuit, an electric motor, and means located upon the vehicle for normally governing the motor operation, of means normally carried upon the vehicle for controlling motor operation from said supply circuit externally to the vehicle.

40 16. In a system of vehicle control, the combination with a substantially constant-voltage supply circuit, an electric motor, and means located upon the vehicle for normally governing the motor operation, of portable means directly utilizing said supply-circuit for controlling motor operation externally to the vehicle.

17. In a system of vehicle control, the combination with a direct-current supply circuit comprising "trolley" and "ground"

conductors, an electric motor, and means located upon the vehicle for normally governing the motor operation, of independent means for effecting motor operation by energy derived only from said conductors, said independent means embodying control means operable from points external to the vehicle. 55

18. In a system of vehicle control, the combination with a propelling motor, of means carried in the hand of the operator for governing said motor and comprising taut electrical connections to effect relative travel of the vehicle and the operator.

19. In a system of vehicle control, the combination with a propelling motor and means located upon the vehicle for normally governing the vehicle operation, of means for rendering said normal control inoperative and for effecting relative travel of the vehicle and the operator. 65

20. In a system of vehicle control, the combination with an electric motor and means located upon the vehicle for normally governing the motor operation, of a brake, and single means external to the vehicle for governing both the motor and the brake. 70

21. In a system of vehicle control, the combination with a propelling motor and means located upon the vehicle for normally governing the vehicle operation, of a brake, and means adapted to be carried externally to the vehicle for releasing said brake and energizing the motor. 80

22. In a system of control, the combination with an electric motor and control means for effecting normal operation of the motor to a predetermined stage, of other control means for effecting motor operation to a different stage. 85

23. In a system of vehicle control, the combination with a propelling motor and control means located upon the vehicle for effecting normal operation of the motor to full speed, of portable control means for effecting slow-speed motor operation. 90

In testimony whereof, I have hereunto subscribed my name this 29th day of Sept., 1917.

KARL A. SIMMON.
